(57) **CLAIM**

The ornamental design for a wall-mounted water bottle filling station, as shown and described.

DESCRIPTION

FIG. 1 is a top, left perspective view of a wall-mounted water bottle filling station, showing our new design;

FIG. 2 is bottom-right perspective view of the wall-mounted water bottle filling station seen in FIG. 1;

FIG. 3 is a front view of the wall-mounted water bottle filling station seen in FIG. 1;

FIG. 4 is a left side view of the wall-mounted water bottle filling station seen in FIG. 1;

FIG. 5 is a right side view of the wall-mounted water bottle filling station seen in FIG. 1;

FIG. 6 is a top view of the wall-mounted water bottle filling station seen in FIG. 1;

FIG. 7 is a bottom view of the wall-mounted water bottle filling station seen in FIG. 1; and,

FIG. 8 is a cross section view thereof, taken along line 8-8 in FIG. 3.

The broken lines in the drawings depict portions of the wall-mounted water bottle filling station that form no part of the claimed design.

1 Claim, 5 Drawing Sheets
